UNITED STATES PATENT OFFICE.

WILLIAM H. DUNN, OF CHICAGO, ILLINOIS.

REMOVABLE REFUSE-CATCHER.

1,390,345.

Specification of Letters Patent. Patented Sept. 13, 1921.

Application filed March 19, 1919. Serial No. 283,600.

To all whom it may concern:

Be it known that I, WILLIAM H. DUNN, a citizen of the United States, residing at Chicago, in the county of Cook and State of Illinois, have invented a certain new and useful Improvement in Removable Refuse-Catchers, of which the following is a full, clear, concise, and exact description, reference being had to the accompanying drawings, forming a part of this specification.

The invention relates to refuse catchers and primarily to that type of these devices which is designed to be removably arranged in a sink or other basin in which such material is liable to accumulate and which for sanitary and other reasons it is desirable to remove.

It is an object of the invention to produce a device of this character which will permit the water to drain from the sink or basin and which will prevent the passage of such matter as would ordinarily clog the waste pipe, and further to provide the device with a depressed or cup shaped portion having a handle whereby the device may be lifted out of its seat so that the material deposited therein may be removed from the basin and from the device without soiling the hands and without the aid of any other instrumentality.

The invention has as an added object the provision of a device of this character which is applicable for use in connection with cleansing machines such as shown and described in the patent issued to me April 30, 1907, No. 851,736.

The invention will be described in this connection, although it is evident that its use is not limited thereto. It is a further object to produce a device of this character which is simple in construction and effective in operation.

The invention will be explained in detail and more readily understood when read in conjunction with the accompanying drawings, in which—

Figure 1 is a view showing the device applied to an ordinary sink;

Fig. 2 is a view showing its application in connection with a cleansing machine;

Fig. 3 is a top plan view of the device shown in Fig. 2;

Fig. 4 is a section taken on line 4—4 of Fig. 3; and

Fig. 5 shows a modified form of construction.

In the particular construction of the device as illustrated in the drawings, an annular member generally designated 1 is contemplated. The member has a laterally extending annular member 2 and a downwardly extending flange 3, this latter portion being of a dimension sufficient to produce the depressed or cupped portion 4, into which any waste or foreign matter may be deposited and retained. A perforated plate 5 is provided, to permit the water to be drained therefrom and to retain the refuse therein. This plate 5 may be fastened to the member 1 in any suitable manner as by the screws 5^b. The construction thus far explained produces an arrangement which may be seated in the orifice 6 usually provided in sinks, tubs or basins.

The explanation of the structure herein-after to be described is particularly applicable for use in connection with a cleansing machine which in a general manner employs the use of a fluid container 12 and a reciprocating or rotating element or circulator 13, as shown in the patent issued to me and hereinbefore referred to. When the device is applied in conjunction therewith the circulator 13 will be provided with the portion 14 which is provided with the recess 15 for the reception of the pivot stud 16 of the device forming the subject matter of this application.

A bridge piece 7 is provided above the annular member and extends across the same and produces a handle whereby the device may be lifted out of the orifice in which it is seated to remove any waste which is lodged therein. This bridge piece is elevated a suitable distance above the member 2 so as not to interfere with the waste material being deposited in the cupped portion 4 and to permit of its being readily emptied.

This bridge piece 7 is provided with the seat 8 having the stud 16 extending therefrom, this latter portion forming a pivot for the circulator 13 which is removably mounted thereon.

From the foregoing it is evident that an arrangement is produced which is applicable for use in the ordinary sink or basin, or with a cleansing machine, which can readily be applied or removed from either when this is desired.

Having shown and described the invention, it is evident that changes and modifications may be resorted to without departing

from the spirit or scope of the appended claims.

What I claim and desire to protect by Letters Patent is:

5. 1. In a device of the class described, the combination of a ring adapted to be inserted into an orifice, said ring being closed by a perforated member, said ring and perforated member producing a receptacle into 10 which material may be lodged, a member extending from said ring and said last mentioned member having means whereby another member may be held in pivotal relation thereto.
15. 2. In a device of the class described, the combination of a member having a portion adapted to be inserted into an orifice and having a perforated depression, a member extending from the first mentioned member, 20 said member having a portion for holding another member in pivotal relation thereto and a seat arranged to support the pivoted member in vertical position relatively to said portion.

3. In a device of the class described, the 25 combination of an annular member adapted to be inserted and removed from an aperture, said member having a depression, said depression having one wall thereof provided with perforations, a bridge piece arranged so as to permit the passage of material below it into the depression and having means whereby another element may be held in 30 pivotal relation thereto, said bridge piece forming a handle whereby said member may 35 be inserted and removed from the orifice.

4. In a device of the class described, the combination of an annular member, a depression provided therein, one wall of the depression being perforated, a bridge piece 40 extending across the depression, said bridge piece having a seat and a stud projecting therefrom whereby another member may be held in pivotal relation thereto.

In witness whereof, I hereunto subscribe 45 my name this 3rd day of March, A. D. 1919.

WILLIAM H. DUNN.
